UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

APPARATUS FOR HANDLING MATERIAL IN CENTRIFUGAL MACHINES.

1,189,920.

Specification of Letters Patent.

Patented July 4, 1916.

Application filed June 13, 1912. Serial No. 703,435.

To all whom it may concern:

Be it known that I, DANIEL M. COOPER, of Rochester, in the county of Monroe and State of New York, have invented certain new and useful Improvements in Apparatus for Handling Material in Centrifugal Machines; and I do hereby declare the following to be a full, clear, and exact description of the same, reference being had to the accompanying drawings, forming a part of this specification, and to the reference-numerals marked thereon.

The present invention relates to the treatment of relatively light materials and articles of small weight, having reference particularly to machines of the type in which material is supported against a rotating basket by the rapid movement of the latter, and is there subjected to the particular action for which the machine is intended.

The invention contemplates a novel process and apparatus for handling such materials, and it has for its object to provide a machine from which the material is automatically discharged, thereby enabling large volumes to be handled expeditiously, and increasing the capacity and efficiency of the machine by obviating the necessity of unloading by hand.

The invention further consists in a novel construction and arrangement of parts which enables the machine to be readily charged, and automatically operating instrumentalities for effecting the treating and discharging of the material at successive predetermined intervals.

To these and other ends the invention consists in certain improvements and combinations of parts, all as will be hereinafter more fully described, the novel features being pointed out in the claims at the end of the specification.

In the drawings: Figure 1 is a view in side elevation of a machine constructed in accordance with a preferred embodiment of the invention; Fig. 2 is a transverse sectional view of Fig. 1, with parts omitted; Fig. 3 is a plan view of one section of the machine, with a portion broken away; Fig. 4 is a detail view in elevation, partly in section, showing the feeding mechanism; Fig. 5 is a detail view in elevation, showing the motor for driving the supports on which the rotary baskets are mounted, and the transmission gear; Fig. 6 is a detail plan

view showing one of the feeding blowers, and a portion of the gearing for driving the supports; Fig. 7 is a view in side elevation, with parts appearing in section, of one of the sections of the machine; Fig. 8 is a detail sectional view showing one arrangement of steam pipes for heating the baskets; Fig. 9 is a sectional view on the line 9^a—9^a of Fig. 3; Fig. 10 is a transverse sectional view on the line 10^a—10^a of Fig. 9, showing one of the brushes in elevation, and Fig. 11 is a diagrammatic view of the electrical controlling means.

Similar reference numerals throughout the several figures indicate the same parts.

The invention may be variously applied in drying, coating or otherwise treating different materials and relatively light articles, and in the present application, I disclose a preferred form of apparatus, primarily designed for treating corks, or cork disks for bottle stoppers or caps although it may be employed in the treatment of other materials as well.

In the machine of the present embodiment, mechanism is provided for successively applying solutions of paraffin and glycerin to corks, or cork disks, the corks being supported against a rotating annular basket having an unobstructed open bottom, and which serves to extract the surplus liquid, leaving the corks free to fall into a suitable discharge when the movement of the basket ceases. In general, the machine includes two sections, one for treating with one material, as paraffin, and the other for subsequently treating with another material, as glycerin, provision being made for feeding the articles to the first section, discharging and feeding them to the second section, and thereafter discharging them from the latter when the operation is completed. Each section includes a plurality of baskets, which may be constructed in any suitable way to afford an unobstructed open bottom, each of the baskets being mounted to rotate, and to revolve about an axis common to all. The baskets of each section are mounted on a rotary support, means being provided for rotating the supports, while each support carries a plurality of motors, corresponding to the number of baskets, each basket being preferably mounted on its motor shaft. The supports are intermittently rotated to bring the several baskets

to the feeding and discharging points successively, while each basket is stopped at predetermined intervals to permit the discharge of the material after it is treated. 5 The material may be fed to the baskets in any convenient manner, this being preferably accomplished in the case of material such as cork disks for bottle stoppers by means of suitable blowers, which place the 10 material in contact with the vertical walls of the baskets, while the latter are rotating, and the discharge of the material is effected by stopping the movement of the baskets, and permitting the material to fall 15 therefrom.

Referring more particularly to the drawings, A and B designate the two sections of the machine, said sections including the supports *a* and *b*, respectively, on which are 20 mounted the baskets or containers arranged within the casings *a*², *a*³, *a*⁴ and *b*², *b*³, *b*⁴, respectively. The several baskets are similarly arranged, and for convenience, I will describe one of these, as shown in Fig. 7, 25 the basket being designated at *a*⁵ and disposed within the casing *a*⁴. The casing *a*⁴ is suitably attached to and carried by a spider *a*⁶ which is mounted on the support *a*. The basket *a*⁵ is preferably inverted, as 30 shown; or otherwise constructed to afford an unobstructed open bottom through which the material is discharged, and is provided with a flaring mouth *a*⁷, and a top portion *a*⁸. The basket is mounted on the 35 shaft *a*⁹, which preferably is part of the motor shaft, the basket driving motors being designated at *A*², *A*³, *A*⁴ and *B*², *B*³, and *B*⁴. The basket *a*⁵ preferably consists of a hollow perforate metal cylinder against the 40 side of which the material is supported. Where the material is to be treated with paraffin, or a similar substance, it is desirable to heat the basket in order to maintain the treating substance in a fluid state, and 45 to this end, I provide a steam pipe *a*¹⁰ supported on lugs *a*¹¹ carried by the brackets *a*¹² which are suspended from the cover plate *a*¹³. Said steam pipe *a*¹⁰ is connected, as shown in Fig. 9, to the inlet pipe *a*¹⁴ and outlet pipe *a*¹⁵. The inlet and outlet pipes are stationarily arranged relatively to the rotating support, and the steam pipe *a*¹⁰ leads to the rotatable member *a*¹⁶ which is connected with the inlet and outlet pipes 55 by means of stuffing boxes *a*¹⁷ and *a*¹⁸ respectively. Thus, each of the three baskets of each section, as shown in the present embodiment, is heated by means of steam pipes leading to the inlet and outlet pipes already 60 mentioned, as shown in Fig. 3. As the basket is rotated, the material is held against its side wall by the centrifugal force, and the treating substance is forced through the material and extracted from 65 the basket, passing outwardly and falling

into a trough *a*¹⁹ which carries a depending spout *a*²⁰, the latter traveling within the stationary trough *a*²¹ from which the treating substance is returned to the point of supply in any suitable manner.

The supports *a* and *b* are mounted on the pedestals *c*, each support being provided with a gear surface *a*²² with which cooperates the pinions *a*²³ mounted on opposite ends of the shaft *a*²⁴. The gear surfaces *a*²² engage above and below the pinions *a*²³ so as to effect movement of the supports *a* and *b* in the same direction from the power shaft *a*²⁴. The power shaft *a*²⁴ carries the gear wheel *a*²⁵ which meshes with the pinion *a*²⁶ arranged on the shaft *a*²⁷, the latter carrying a worm wheel *a*²⁸ with which engages the worm *a*²⁹ mounted on the shaft *a*³⁰ of the motor *D*. Thus, the motor *D* drives both supports, causing the baskets of the two sections to revolve about their respective axes, and the motor *D* is controlled by the movement of the supports, in a manner that will be hereinafter described more fully, so as to effect stopping and starting of the supports at predetermined intervals for a purpose that will appear.

The material is fed to the machine in any suitable manner, and to this end, in the present embodiment, there are provided feeding tables *a*³¹, having perforate bottoms *a*³², formed of wire gauze or similar material, and side walls *a*³³. The feeding tables *a*³¹ are mounted on vertically disposed arbors *a*³⁴, to the lower ends of which are secured pinions *a*³⁵ which mesh with the bevel gears *a*³⁶ arranged on the shafts *a*³⁷, the latter being provided with worm wheels *a*³⁸ in engagement with cooperating worms *a*³⁹ on the shaft *a*⁴⁰. Clutches *a*⁴¹ are provided, adapted to be controlled by hand levers *a*⁴², for starting and stopping the feed tables, to feed the material to the machine. The shaft *a*⁴⁰ carries a pulley *a*⁴³ which is driven from the motor *E* by means of the belt *a*⁴⁴.

The material is fed by means of suitable blowers *a*⁴⁵ which are driven from the shaft *a*⁴⁶ by means of the belt connections *a*⁴⁷. The motor *E* is driven continuously, so that the blowers are constantly operated, while the movement of the feeding tables may be stopped by disengaging the clutches *a*⁴¹, as previously noted. The blowers *a*⁴⁵ are provided with upwardly directed outlets *a*⁴⁸ which terminate beneath the feeding tables as shown in Fig. 7. Arranged above the feeding table, and in vertical alinement with the outlets *a*⁴⁸, are the conducting spouts *a*⁴⁹, the upper portions of which are curved, as shown in Fig. 4, so as to direct the material into the baskets at an angle, and against the side walls thereof. Arranged about the spouts *a*⁴⁹ are hoppers *a*⁵⁰ which are supported on brackets *a*⁵¹, and serve to conduct the surplus material that may fall from the

basket back to the feeding table through the opening a^3 . The material is supplied to the feeding table in any convenient manner, and as the feeding table a^1 rotates, the particles are blown upwardly through the spout a^4 against the side wall of the basket, and held in contact therewith by its rapid rotation.

The treating substance is injected into the basket in any suitable manner, and in the present embodiment, I accomplish this by means of a spray a^5 which is arranged within the hopper a^6 and angularly disposed, as shown in Fig. 4, in order to direct the substance into contact with the wall of the basket and against the material. The spray a^5 is arranged at the end of the liquid supply pipe a^7 which is provided with a hand operated valve a^8 for shutting off the supply of treating substance when desired. While the treating substance may be applied in different ways to the interior of the basket, I prefer the arrangement which I have herein shown and described, and it is preferably admitted simultaneously with the upward movement of the material to be treated. In the embodiment shown, the parts are arranged for the treatment of corks such as are used in metal caps for sealing bottles. The section of the machine designated at A, is supplied with paraffin in a liquid state, while section B is supplied with glycerin. In the normal operation of the parts, two of the baskets of each section are rotating while the other one is stationary, for the purpose of discharging its contents. After such discharge, the support is turned sufficiently to bring the stationary basket over the spout a^4 and at the same time, the basket is set in rotation. The feeding table is operated by engaging the clutch a^9 and the rotating basket is charged with material and with the treating fluid. The support is again moved to bring the next basket above the feeding point, the first mentioned basket continuing to rotate, so as to cause the treating fluid to thoroughly cover the corks, and to be extracted from the basket. The support is again stopped, until the next basket is charged, and upon further movement of the support, the first mentioned basket is brought to its initial position, at which point the basket ceases to rotate and the contents permitted to fall therefrom, dropping into a chute a^{10} which conducts the material that is treated in the first section A, to the feeding table of the second section B, where the same operation is repeated with glycerin. A chute a^{11} leads from the discharging point of the section B to carry off the material after which it may be handled and disposed of in any desired manner.

The starting and stopping of the supports, and of the brackets on the supports, is effected through mechanism which is con-

trolled by the movement of the supports, and in Fig. 11, I have shown, diagrammatically, a preferred arrangement of circuits, and connections with the different motors for effecting the intermittent movement of the supports and baskets previously described, and while this operation may be accomplished in various ways, I prefer an electrical controlling means, and the particular construction and arrangement thereof of which I will now describe. Each support a, b is provided with a pair of rings a^{12} on which are mounted the switches a^{13} and b^{13} , which control the motors A^2, A^3, A^4 and B^2, B^3, B^4 respectively. The rings a^{12} are connected by vertical standards a^{14} , which support the brushes, or movable contacts a^{15} , which travel with the support and engage the stationary conductors which will now be described. a^{16}, b^{16} are continuous rings connected to the positive side of the main circuit C to which current is supplied in any suitable manner. The negative side of said circuit C is connected to the continuous rings a^{17}, a^{18}, a^{19} and a^{20} ; $a^{17}, a^{18}, a^{19},$ $b^{17}, b^{18}, b^{19}, b^{20}$ and b^{21} , are conducting segments arranged as shown, for a purpose that will presently appear, while a^{12}, a^{13} and b^{12}, b^{13} are segmental sections of a conducting ring, which are connected as shown to the stationary contacts a^{15} , the latter being arranged to be engaged successively by the movable contacts a^{16} , which are mounted on a ring a^{22} carried on the shaft of the time-controlling motor a^{23} . The motor a^{23} is operated from circuit C, as shown, and determines the periods of movement of the supports a, b on which the baskets are mounted. The conducting rings and segments just described are supported from the ceiling, or other stationary part, by means of the standards a^{24} and the posts a^{25} adjustably mounted thereon. As the supports rotate, the brushes a^{15} engage the different conductors successively, and through the time controlling motor a^{23} , effect the starting and stopping of the principal motor D which operates the supports, and of the basket controlling motors A^2, A^3, A^4 and B^2, B^3, B^4 . The time-controlling motor a^{23} operates continuously at a given rate of speed determined by the speed controlling device a^{26} .

In the position shown in Fig. 11 the support a, b , are stationary, as are also the motors A^2 and B^2 . The circuits through the motors A^3 and B^3 are closed as follows: from conducting ring a^{16} through the series field of motor A^3 to conductor a^{18} , to conductor b^{19} , to the series field of motor B^3 , to conducting ring b^{21} . Between the conductors a^{18} and b^{19} , a connection leads to the armature a^{27} of the electromagnet F, and thence to negative conductor a^{23} . The circuit is closed to start the motor A^3 and B^3 , the electromagnet F being energized from the main

circuit through the conductor b^1 and conductor a^6 . As soon as this circuit is made, the armature a^2 is drawn over, closing the circuit already described, and operating the 5 motors A^2 , B^2 , and the baskets supported thereby. At the same instant, the circuits to the motors A^4 and B^4 are broken, and their armature shafts are running from their own momentum. In the same position, the 10 motors A^2 and B^2 are stationary, the stopping of their movement being effected by short circuiting their armatures in the following manner: Current passes from the conductor a^6 through the armature of motor 15 A^2 to conductor a^7 to the resistance a^8 to electromagnet a^9 , through the electromagnet a^9 and back to the conductor a^6 , the armature a^8 having previously been drawn over to close said circuit by the current 20 through conductor b^1 . Immediately, the current through the armature of the motor becoming weaker, the armature a^8 falls back to the position shown, completing a circuit from armature a^8 , to electromagnet a^9 , and 25 thus closing a circuit through armature a^8 , and cutting out the resistance a^8 . While I have shown only one resistance element a^8 , it will be understood that I may employ a plurality of these, with means for 30 successively cutting them out of the circuit so as to bring the motor to a quick stop without injury to any of the parts. As soon as the motor a^8 operates sufficiently to bring another contact a^9 into engagement with 35 its corresponding stationary contact a^8 , a circuit is completed from conductor a^7 through electromagnet a^9 . The armature a^8 is thereby drawn over, closing the circuit through the motor D , and causing the support 40 to turn, until they move far enough to break the circuit, when the operation just described is repeated.

While I have shown and described a particular arrangement of the parts it will be 45 understood that the construction set forth may be modified and changed without departing from the essential features of my invention, and I intend to cover by this application any applications of the invention 50 which come within the scope and terms of the claims hereinafter, comprehending a rotatable basket for supporting materials to be operated upon, and having an unobstructed open bottom through which the material 55 may be discharged when the basket is brought to a stop.

I claim as my invention:

1. The combination with a rotary support, of a plurality of baskets mounted on 60 the support and rotatable thereon independently of the movement of the support, and mechanism controlled by the rotation of the support for arresting and starting the rotation of the baskets at predetermined intervals.

2. The combination with a rotary support, of a plurality of baskets mounted on the support and rotatable thereon independently of the movement of the support, and mechanism controlled by the rotation of the support for arresting and starting the rotation of the baskets at predetermined 70 intervals.

3. The combination with a rotary support, of a plurality of baskets mounted on 75 the support and rotatable thereon independently of the movement of the support, and mechanism controlled by the movement of the support for arresting and starting the support at predetermined intervals, and for 80 starting and arresting the rotation of the baskets at predetermined intervals.

4. The combination with a movable support, of a plurality of baskets mounted on the support and rotatable thereon independently of the movement of the support, each of said baskets having an unobstructed, 85 open bottom, and mechanism controlled by the movement of the support for arresting and starting the support at predetermined 90 intervals.

5. The combination with a movable support, of a plurality of baskets mounted on the support and rotatable thereon independently of the movement of the support, each of said baskets having an unobstructed open 95 bottom, and mechanism controlled by the movement of the support for starting and arresting the rotation of the baskets at predetermined intervals. 100

6. The combination with a movable support, of a plurality of baskets mounted on the support and rotatable thereon independently of the movement of the support, each of said baskets having an unobstructed open 105 bottom, and mechanism controlled by the movement of the support for arresting and starting the support at predetermined intervals and for starting and arresting the rotation of the baskets at predetermined intervals. 110

7. The combination with a rotary support, of a motor having connection with the support for operating the same, a plurality of baskets rotatably mounted on the support, and a plurality of motors operatively connected with the respective baskets, said motors also being mounted on the support. 115

8. The combination with a rotary support, of a motor having connection with the support for operating the same, a plurality of baskets rotatably mounted on the support, a plurality of motors operatively connected with the respective baskets, said motors also being mounted on the support, and mechanism controlled by the movement of the support for arresting and starting movement of the motors at predetermined intervals. 120

9. The combination with a basket having 125

- an open bottom, of mechanism for placing material to be operated upon in contact with the vertical walls of the basket while the latter is in rapid rotation and including an upwardly directed discharge spout near the bottom of the basket acting to direct the material upwardly and into engagement with the walls of the basket, and means for arresting the rotation of the basket to permit discharge of the material. 5
10. The combination with a basket having an open bottom, of an upwardly directed discharge spout located near the bottom of the basket and acting to direct the material to be operated upon upwardly and against the wall of the basket, a blower arranged beneath the basket and coöperating with said discharge spout for feeding material, and a pipe directed toward the interior of the basket for applying a treating substance. 15
11. The combination with a basket having an open bottom, of an upwardly directed discharge spout located near the bottom of the basket and acting to direct the material to be operated on upwardly and against the wall of the basket, a blower arranged beneath the basket and coöperating with said discharge spout to force the material upwardly into the basket, a pipe directed into the basket for applying a treating substance to the material to be operated on, and heating coils surrounding the basket. 20
12. The combination with an intermittently rotatable support, of a plurality of independently rotatable baskets arranged thereon and open at the bottom to permit the automatic discharge of material therefrom, separate motors for rotating said baskets, means for loading material into said baskets while in rapid rotation, and controlling devices actuated by the movement of the support for starting and arresting the movement of said motors to automatically effect discharging of the baskets. 25
13. The combination with an intermittently rotatable support, of a plurality of independently rotatable baskets arranged thereon and open at the bottom to permit the automatic discharge of material therefrom, separate motors for rotating said baskets, means for loading material into said baskets while in rapid rotation, and controlling devices actuated by the movement of the support for effecting the intermittent movement of the support and for starting and arresting movement of said motors to automatically effect discharging of the baskets. 30
14. The combination with an intermittently movable support, of a plurality of independently rotatable baskets arranged thereon and open at the bottom to permit the automatic discharge of material therefrom, separate motors for rotating said baskets, means for loading material into said baskets while in rapid rotation, and controlling devices actuated by the movement of the support for starting and arresting the movement of said motors to automatically effect discharging of the baskets. 35
- said baskets while in rapid rotation, and controlling devices actuated by the movement of the support for starting and arresting the movement of said motors to automatically effect discharging of the baskets. 40
15. The combination with an intermittently rotatable support, of a plurality of independently rotatable baskets arranged thereon and open at the bottom to permit the automatic discharge of material therefrom, separate motors for rotating said baskets independently, means for loading material into said baskets while in rapid rotation, and automatic controlling devices for starting and arresting movement of said motors to effect discharging of the baskets. 45
16. The combination with a rotatable support, of a plurality of independently rotatable baskets arranged thereon and open at the bottom to permit the automatic discharge of material therefrom, a plurality of troughs carried by said support and arranged about the respective baskets to catch the surplus treating fluid discharged from the baskets, a stationary trough arranged below the baskets, and discharge spouts carried by the first mentioned troughs and arranged for travel in said stationary trough. 50
17. The combination with a rotatable support, of a plurality of independently rotatable baskets arranged thereon and open at the bottom to permit the automatic discharge of material therefrom, separate motors for rotating said baskets independently, means for loading material into said baskets while in rapid rotation, said means comprising a feeding table, conducting spouts arranged above the feeding table and extending upwardly therefrom, and a blower disposed beneath the feeding table and in alignment with the aforesaid spouts. 55
18. The combination with a stationary pedestal, of a support rotatably mounted thereon, means coöperating with the support for rotating the same, a plurality of independently rotatable baskets arranged on the support and having open bottoms to permit the automatic discharge of material therefrom, separate motors on the support for rotating said baskets, and means for loading material into the baskets while in rapid rotation. 60
19. The combination with a rotatable support, of a plurality of independently rotatable baskets arranged thereon and open at the bottom to permit the automatic discharge of material therefrom, separate motors for rotating said baskets independently, means for loading material into said baskets while in rapid rotation, means for applying a treating substance onto the material while in the baskets, heating coils surrounding each of said baskets and mounted on the support, troughs arranged on the support below said heating coils and surrounding the 65

- baskets, a stationary trough, and discharge spouts carried by the first mentioned troughs and arranged to travel in said stationary trough.
- 5 20. The combination with an intermittently rotatable support, of a plurality of independently rotatable baskets arranged thereon and open at the bottom to permit the automatic discharge of material therefrom, separate motors for rotating said baskets, means for loading material into said baskets while in rapid rotation, and electrical devices controlled by the movement of the support for braking said motors quickly to permit a discharge of the material from the baskets.
- 10 21. The combination with a stationary pedestal, of a support rotatably mounted thereon, means coöperating with the support for rotating the same, a plurality of casings carried by the support, troughs arranged at the bottoms of the casings, a plurality of independently rotatable perforate baskets having open bottoms arranged on the support and within said casings, a stationary trough, discharging spouts mounted on the first mentioned troughs and arranged to travel in said stationary trough, means for loading material into said baskets while in rapid rotation, and means for applying a treating substance onto the material while in the baskets.
- 15 22. The combination with an intermittently rotatable support, of a plurality of independently rotatable baskets arranged thereon and open at the bottom to permit the automatic discharge of material therefrom, separate motors for rotating said baskets, means for loading material into said baskets while in rapid rotation, a plurality of stationary conductors, brushes arranged on the support and adapted to engage said conductors, and devices controlled by the movement of said support for effecting the starting and arresting of said motors. 45
- 20 23. In combination with a stationary, hollow pedestal, a support rotatably mounted thereon, means coöperating with the support for rotating the same, a plurality of casings carried by the support, a plurality of independently rotatable perforate baskets having open bottoms mounted on the support and arranged within the casing, steam pipes extending within said hollow pedestal, heating coils arranged about the respective baskets and connected with the aforesaid steam pipes, means for loading material into the baskets while in rapid rotation, and means for applying a treating substance onto the material while in the basket. 50
- 25 24. In combination with an intermittently rotatable support, a plurality of independently rotatable baskets arranged thereon, separate motors for rotating said baskets, and electrical means controlled by the movement of the support for braking said motors. 55
- 30 25. In combination with an intermittently rotatable support, a plurality of independently rotatable baskets arranged thereon and open at the bottom to permit the automatic discharge of material therefrom, separate motors for rotating said baskets, and electrical means controlled by the movement of the support for braking said motors to permit discharge of the material, and for effecting intermittent movement of the support. 60
